UNITED STATES PATENT OFFICE.

HJALMAR G. CARLSON, OF WORCESTER, MASSACHUSETTS, ASSIGNOR, BY MESNE ASSIGNMENTS, TO ROCKWOOD SPRINKLER COMPANY OF MASSACHUSETTS, OF WORCESTER, MASSACHUSETTS, A CORPORATION OF MASSACHUSETTS.

METHOD OF FORMING A PRESSED METAL ARTICLE.

1,389,739.

Specification of Letters Patent.

Patented Sept. 6, 1921.

Application filed September 17, 1918. Serial No. 254,481.

To all whom it may concern:

Be it known that I, HJALMAR G. CARLSON, a citizen of the United States, residing at Worcester, in the county of Worcester and 5 State of Massachusetts, have invented a new and useful Method of Forming a Pressed Metal Article, of which the following is a specification.

This invention relates to a method of producing from a flat sheet metal blank a tubular article having one end of materially thicker stock than the other, but integral with the tubular portion. Such an article can be formed for any desired purpose.

15 The invention involves the process of gradually producing such an article by a series of cold drawing operations and doubling over its end in dies so as to render the end portion of more than double thickness 20 as described. Further objects and advantages of the invention will appear hereinafter.

Reference is to be had to the accompanying drawings, in which—

25 Figure 1 is an edge view of a circular blank of soft sheet metal from which the article is to be produced, and

30 Figs. 2 to 12 inclusive are longitudinal central sectional views of the blank in several stages of its production, the order of the steps being indicated by the numerals designating the several figures, Fig. 12 showing the completed article so far as the metal drawing operations are concerned.

35 The invention is shown herein as being employed for the production of a combination booster casing and adapter for a shell, the adapter being integral with the booster casing and being formed with a doubled over 40 external flange as indicated above. This is a cold drawn article, but of course the metal is annealed as many times as may be necessary. The article, of course, can be made in any desired size or shape, but the one

45 illustrated is made from a circular blank 10 of annealed sheet stock as indicated in Fig. 1. This is shaped by dies to produce by the first operation a flanged cup such as indicated in Fig. 2. By this operation the center of the blank is drawn out to form a central cup-shaped portion 12 having a circumferential flat edge 11 at the open end. The

diameter of the blank is reduced by this operation and the metal is only slightly thickened at the edge.

55 The second operation, the result of which is indicated in Fig. 3 is shown mainly for the purpose of flattening and thinning the base 13 of the blank. The thinning however may be omitted in some classes of work. 60 The internal and external diameters of the walls between the base and edge flange 11 are reduced by this operation and the length of the cylinder increased. The thickness of the flange 11 is unchanged although as this 65 flange is not held between flat surfaces it becomes curved.

70 The third operation changes the shape of the blank shown in Fig. 3 to that shown in Fig. 4, in which the edge flange 11 is not materially increased in area. The internal and external diameters of the tubular portion are materially reduced, the thickness of the stock everywhere remaining substantially the same.

75 By the next operation indicated in Fig 5 again the only change produced is the reduction in diameter of the cylindrical portion of the blank and lengthening it.

80 The next operation also is for a similar purpose, the diameter being reduced slightly and the length increased. This result is indicated in Fig. 6.

85 It will be seen that Figs. 4, 5 and 6 represent the results of three operations, each of which has for its object merely the reduction in diameter and the increase in length of the cylindrical portion of the blank. No change in thickness is intended anywhere, but it is found that the diameter of the flange 11 may 90 be increased slightly, and of course its width is materially increased.

95 The next operation, the result of which is shown in Fig. 7, also involves the lengthening of the tubular portion, but by the reduction of its end only. The open end 14 of the tube near the flange 11 is left in the same condition as in Fig. 6, but the closed end is drawn out between the die and plunger, not shown, so as to reduce the diameter and increase the length proportionately.

100 The result of the next operation is the shape shown in Fig. 8. It will be noted that

the flange 11 has a wavy shape, a circular corrugation being formed in it. This is provided to store a surplus of metal here so that in performing the next operation shown 5 in Fig. 9 there will be stock to force into the square corners of the dies and fill them up to produce the shoulder 17. The edge is now trimmed off to a true cylindrical surface to exactly fit the dies shown in Fig. 8 and 10 hold the metal so that the square shoulder can be formed by means of these dies. The flange 11 is flattened out, or its flattening completed, between the flat die plates. When 15 the cup leaves the dies shown in Fig. 8 its shoulder 15 is nearly square and its flange is flat. Preferably a corrugation 18 is then formed in the edge of the flange to produce the shape shown in Fig. 9.

Having brought the blank to this form, 20 the thin tubular portion 16 is in its final shape as is also the thickened portion 14 at the base. The flange 11 is the only thing that now remains to be shaped, and this is bent over by forcing it through a die and assumes the form shown in Fig. 10. It now constitutes an external rim 11^a of circular shape spaced from the inner wall 14.

Two operations in forming dies force this 25 rim 11^a up against the surface of the wall 14. The results of these operations are shown in Figs. 11 and 12. Fig. 11 shows the rim drawn in and Fig. 12 shows it upset against the wall 14. In the final condition this rim 11^a constitutes an integral external wall 30 of conical shape connected with the internal wall 14 at the end, which in turn is integral with the tubular casing 16 below. It is to be observed that the upsetting causes both walls 11^a and 14 to be materially thicker than the 35 wall 16. I have shown the rim 11^a as extending beyond the shoulder 15 which connects the tubular casing 16 with the inner wall 14.

A feature shown in Fig. 12 is the anchoring 40 of the rim 11^a to the wall 14 on the outside. As the rim 11^a is upset longitudinally and is forced in over the shoulder 17, its inner surface assumes a barrel shape and gives the wall 14 a corresponding form fitting in it. This anchors the two parts together. Thus, if any weakness develops 45 where the rim is bent over, it tends to be compensated for by this construction. When it is desired to still further strengthen this part of the article the corrugation 18 is provided. This furnishes surplus metal for 50 forming a solid projection 19 which is drawn in behind the shoulder 17 and absolutely prevents the fracture of the article where the rim is turned over. It also makes the rim 55 11^a very thick and rigid so that it will stand threading without being unduly weakened.

The external conical surface of the rim 60 11^a is to be provided with a pipe thread if the device is to be used as an adapter. The 65 inner wall also is to be provided with an in-

ternal screw-thread for receiving an internal element whenever that is desired. The part of the rim at the end beyond the screw thread is shown as octagonal in form so that it may be screwed in by a wrench as usual. 70 This is formed in the last operation.

It will be seen, therefore, that by a series of operations such as described above, a flat blank of sheet stock can be converted 75 into a tubular structure having comparatively thin end and side walls and provided with a base having walls of double thickness, each of the latter walls being of greater thickness than the original blank, and that this furnishes a solid and firm base 80 integrally connected with the tubular casing which it supports. Such an article can be used as a combined adapter and booster casing in a shell, but the process can be used for manufacturing articles of other various 85 kinds requiring similar properties.

I am aware, of course, that the exact number of steps set forth herein is not absolutely essential to all kinds of articles that can be made by this process; for example, the three 90 steps represented by Figs. 4, 5 and 6 can be replaced by two or four steps if the particular conditions require it, and the same is true of the operations represented by Figs. 95 7, 8 and 9. Moreover in making adapters for other shells modifications within the skill of any person skilled in the art may be made in this process without departing from the scope of the invention as expressed in the claims. Therefore, I do not wish to be limited 100 in these respects, but what I do claim is:—

1. The method of making an article having a hollow closed end and a double-walled open end, which consists in drawing out a 105 flat blank of cold drawn sheet stock into an elongated tubular shape with one end closed and reduced in thickness and the other end having a circular flange surrounding it, then reducing and elongating the closed end only 110 of the blank by a series of steps, and finally turning over the flange so as to envelop the adjacent wall of the blank.

2. The method of making an adapter and booster casing which consists in drawing out a flat blank of sheet stock into an elongated tubular shape with one end closed and the other end having a circular flange surrounding it, then reducing and elongating the closed end of the blank by a series of drawing operations, leaving the open end of that 115 part of the blank unreduced in diameter and thickness, and turning over the flange into contact with the adjacent convex wall of the blank beyond the unreduced portion to hold 120 the two parts together.

3. The method of drawing sheet metal stock which consists in drawing out a projection from a blank, leaving the open edge 125 in the form of a surrounding flange, form-

ing a shoulder on the projection, doubling over the flat flange to form a rim surrounding the open end of said projection, and finally forcing the rim against the wall 5 which constitutes the end of the projection and behind said shoulder.

4. The method of cold drawing sheet metal which consists in drawing out a tubular projection from a flat circular blank, 16 leaving the open edge in the form of a surrounding flange, annealing it at suitable intervals, elongating and reducing in diameter the tubular projection, thereafter maintaining the portion of this tubular projec- 15 tion near the open end in substantially uniform condition, and while in that condition drawing out the closed end of the same so as to increase its length and reduce its diameter and thickness, forming a shoulder at the 20 end of the thicker portion of the same, doubling over the flange so as to form a rim surrounding the thick portion and projecting beyond said shoulder, and finally forcing the same against the inner wall to bring the 25 rim at its edge beyond the shoulder, upsetting the rim and giving it a conical shape outside.

5. The method of drawing sheet metal stock which consists in drawing out in dies 30 a central projection from a flat circular blank, leaving the open edge in the form of a surrounding flange, progressively drawing out the closed end so as to increase its length and reduce its diameter and thickness 35 at the end, forming a shoulder on the thicker portion of the same, doubling over the flat flange, and finally forcing the same against

the inner relatively thin wall which constitutes the end of the tubular part and over 40 said shoulder.

6. The method of drawing sheet metal which consists in drawing out in dies a central projection from a flat circular blank so as to leave the open edge in the form of a surrounding flange, forming a circumferential shoulder on the projection, doubling over the flange, and finally forcing the same toward the inner wall to bring the external wall or flange at its edge beyond the shoulder, and upsetting the projecting edge 50 against said shoulder.

7. The method of cold drawing sheet stock which consists in drawing out in dies a central projection from a flat circular blank so as to leave the open edge in the form of a 55 surrounding flange, progressively elongating and reducing in diameter the central portion thereof to form a tubular shape, maintaining the portion of this tubular part near the open end in substantially uniform condition, 60 while in that condition progressively drawing out the closed end of the same so as to increase its length and reduce its diameter, forming a shoulder on the thicker portion of the same, doubling over the flange, and 65 finally forcing the same against the thick wall, forcing its end over said shoulder and upsetting it longitudinally to give the inner surface of the flange and the outer surface of the thick wall an interlocking convex or 70 barrel shape.

In testimony whereof I have hereunto affixed my signature.

HJALMAR G. CARLSON.
